OTHER PUBLICATIONS

Office Action issued on Feb. 1, 2024, in related U.S. Appl. No. 29/917,072, 11 pages.

Primary Examiner — Patricia A Palasik(74) *Attorney, Agent, or Firm* — XSENSUS LLP(57) **CLAIM**

The ornamental design for a cutting tool insert, as shown and described.

DESCRIPTION

FIG. 1 is a front view of a cutting tool insert in accordance with the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a cross sectional view taken along line 9-9 of FIG. 1;

FIG. 10 is an enlarged view of portion 10 of FIG. 9; and, FIG. 11 shows a cutting tool insert in an environment of use thereof.

The broken lines shown in the drawings represent portions of the cutting tool insert that form no part of the claimed design.

1 Claim, 6 Drawing Sheets(56)
